UNITED STATES PATENT OFFICE.

RODGER EADES, OF WINCHESTER, KENTUCKY.

HEMP-BRAKE.

1,327,533.

Specification of Letters Patent.

Patented Jan. 6, 1920.

Application filed February 26, 1918. Serial No. 219,268.

To all whom it may concern:

Be it known that I, RODGER EADES, a citizen of the United States, residing at Winchester, in the county of Clark and State 5 of Kentucky, have invented new and useful Improvements in Hemp-Brakes, of which the following is a specification.

This invention relates to hemp brakes, and one of the objects of the same is to provide a double machine, or, one embodying two complete brake organizations at opposite extremities operatively connected to intermediate driving mechanism and whereby the organizations may be simultaneously or 15 individually actuated to treat hemp with advantages in the output of machines of this class and economy in the utilization of driving power. A further object of the invention is to generally improve the mechanical 20 structure of hemp brakes to render them portable and more efficient in operation as well as convenient in assemblage and adjustment to accommodate various working contingencies and the general character and 25 kind of hemp to be treated thereby.

With these and other objects in view, the invention consists in the construction and arrangement of the several parts which will be described more fully hereinafter and 30 pointed out in the claims.

In the drawings:

Figure 1 is a top plan view of a machine embodying the features of the invention.

Fig. 2 is a side elevation of the machine 35 showing one extremity broken away and in longitudinal section.

Fig. 3 is a transverse vertical section taken through the central portion of the machine.

Fig. 4 is an end elevation of a portion of 40 one end of the machine.

Fig. 5 is a detail transverse sectional view of a preferred form of clutch used to connect and disconnect the beating members relatively to the driving mechanism and 45 showing the clutch members in release or loose positions.

Fig. 6 is a view similar to Fig. 5 showing the clutch members in engaged positions.

Fig. 7 is a front elevation of the clutch 50 on a smaller scale.

The numeral 1 designates a bed frame mounted on bolsters 2 supporting axles 3 having ground wheels 4 by which the machine is rendered conveniently portable.

55 The bed frame 1 in the present instance comprises longitudinal side beams 5, end

cross beams 6, intermediate cross beams 7 on opposite sides of the center, and an intermediate floor 8 between the beams 7 for the support of a motor or engine 9 of the hydro-carbon fuel or other type adapted for the purpose and provided with a drive shaft 10 having a drive sprocket 11 thereon. Rising from the bed frame 1 adjacent to the cross beams 7 are pairs of uprights 12 connected 60 by upper cross beams 13, and on these uprights 12 outer and intermediate longitudinal top beams 14 and 15 are securely mounted for the support of the several mechanisms which will be more fully hereinafter described. 65

At each extremity of the machine and extending from the opposite pairs of uprights 12 to the end cross beams 6 of the bed frame 1 is a beating bench comprising a lower open frame 16 which is held in a substantially horizontal plane and has in the present instance a series of four longitudinally extending blades or swords 17 with upper reduced edges and an upper vertically oscillatable open frame 18 having a series of three blades or swords 19 provided with lower reduced edges and longitudinally disposed to align with the spaces between the blades or swords 17. The lower open frame 16 80 is adjustably connected at its inner end between the pairs of uprights 12 through the medium of a rod or boat 20 at each side of the inner end of said frame and engaging transversely alined openings of a series of 90 similar openings 21 formed in the said members and whereby this lower frame may be adjusted vertically to adapt the same to treating hemp of different thickness or other characteristics where adjustment may be required to thoroughly carry out the operation sought. The outer end of the lower frame is yieldingly sustained through the medium of a spring 22 disposed between shims 23 located adjacent to the center of 95 the lower edge of the outer end of the frame and the center of the end cross beam 6 directly beneath said frame end. The shims 23 may be increased or decreased in accordance with the adjustment of the lower frame 100 and to modify the tension of the spring 22, the yielding action of the outer end of this lower frame being rendered positive through the medium of a rod 24 secured to the frame and extending downwardly through the 110 springs and shims into a socket 25 in the adjacent end cross beam 6. This spring at-

tachment or yielding means serves as a spring buffer to keep the machine from being choked and to assist in causing the herds to fall out during the combined action of the upper and lower frames on the hemp. The upper frame 16 is free at its outer end and is hinged or pivoted, as at 26, at its inner end between the uprights 12, the said upper frame as will be understood performing the beating action relatively to the hemp manually placed on the lower frame. The top of the upper frame at the center is provided with two longitudinal bars 27 extending full length thereof and provided with a plurality of openings 28 for the adjustable attachment therebetween of the lower end of a connecting rod 29 extending up to and attached to a wrist or crank pin 30 of a clutch wheel 31 loosely disposed on the inner end of a shaft 32 mounted in suitable bearings 33 on the upper sides of the one top beam 14 and next adjacent intermediate beam 15, the shafts 32 at opposite extremities of the machine or in connection with the two benches being in reverse positions, or both shafts being on the right-hand side if each bench is intended to be actuated by a right-hand operator. For left-hand operators the shafts may be disposed on opposite sides as will be obvious. A depending shifting lever 34 is mounted to the right of each bench and fulcrumed on a bracket arm 35 projecting outwardly from the lower edge of the right-hand top beam 14, and to the upper end of this lever 34 a slide rod 36 is connected and extends inwardly over the beam 14 and adjacent intermediate beam 15 in suitable bearings 36 and secured to a fork 37 which engages a grooved shifting sleeve 38 of a disk 39 slidably keyed to the shaft 32. The disk carries pivotally mounted shoes 40 thereon, as shown by Figs. 5, 6 and 7, said shoes being secured to the sleeve 38 by rods 41 operable by reverse movements of the sleeve to move the shoes outwardly and inwardly on the disk. The disk 39 with its shoes is mounted within the clutch disk or wheel 31 which has a flange 42 for engagement by the shoes. When the shoes are spread or moved outwardly, they impinge or tightly bite against the flange 42 of the clutch disk 31. The fork 37 is moved inwardly by throwing the shifting lever 34 outwardly, and the motion of the shaft 32 through the clutch disk 39 and the shoes carried by the latter is transmitted to the clutch disk 31 and thence through the connecting rod 29 to the upper frame 18 to regularly oscillate the latter or swing the same vertically, as indicated by dotted lines in Fig. 2.

In suitable bearings 43 mounted on the outer top beams 14 is a transversely disposed motion-transmitting shaft 44 having a sprocket wheel 45 thereon over which a

chain belt 46 is trained and also over the drive sprocket 11 of the shaft 10 of the motor or engine. The shafts 32 at the opposite extremities of the machine are arranged to operate the upper frames 18 of the benches each receives its motion from a sprocket wheel 47 keyed on the shaft 44 and having a chain belt 48 engaging the same and a sprocket wheel 49 on each shaft 32, the chain belts 48 extending in reverse directions from their respective sprocket wheels 49, as shown by Fig. 1. By the operation of the clutch mechanism hereinbefore explained, the frames 18 may be simultaneously or independently operated and the operators at each end of the machine will not in the least interfere with each other in their work of feeding the machine and arranging the hemp for beating treatment. Moreover, either one or both extremities of the machine or both benches may be operated as desired or when found necessary, and when the use of one bench only is required, the clutch mechanism of the other bench may be so adjusted as to cause the frame 18 thereof to remain inactive. Moreover, the clutch mechanisms may be operated to disengage the clutch disks 31 at the time that the upper frames 18 are elevated so that the operators may conveniently arrange the hemp on the lower bed prior to the beating oscillation of the upper frames.

It will be understood that the blades or swords 17 and 19 will be so mounted that they may be readily replaced when found necessary and they will be shaped to the best advantage in effecting the beating of the hemp, and, as shown, they diverge from their outer toward their inner extremities, thus providing a most extended blade or sword-beating aggroupment adjacent to the inner extremities of the blades or swords.

The improved machine will be found exceptionally advantageous in thoroughly beating or treating the hemp as required to liberate the fiber thereof and will operate to give an increased output of the treated product.

I claim as my invention:

1. In a hemp brake, a portable base frame, a braking bench at each extremity of the frame including a lower frame held in substantially horizontal position and an upper frame hinged at its inner end to move upwardly from and downwardly toward the lower frame, the frames having co-operating swords, main driving mechanism between the two benches, and independent actuating mechanism for each of the upper frames and connected to the main driving mechanism, each actuating mechanism having an independently operable clutch and clutch wheel, the clutch wheels being connected to the upper hinged frames for causing the said frames to operate either simul- 130

taneously or individually and also for permitting the upper frames to be manually raised.

2. In a hemp brake, a portable base frame, 5 a braking bench at each extremity of the frame including a lower frame held in a substantially horizontal position and adjustably connected at its inner end and an upper frame hinged at its inner end to move 10 upwardly from and downwardly toward the said lower frame, the two frames having coöperating swords, main driving mechanism, and independent actuating mechanism disposed at opposite locations relatively to 15 and connected to the main driving mechanism and respectively connected to the upper frames and independently disconnectible with relation to the main driving mechanism and said upper frames.
- 20 3. In a hemp brake, a base frame, a braking bench at each extremity of the frame including a lower frame normally held in substantially horizontal position and

vertically adjustable to vary the elevation thereof and also provided with spring cushion devices at the outer ends, and an upper frame hinged at its inner end to move upwardly from and downwardly toward and over the said lower frame, the said bench frames having coöperating swords, main 30 driving mechanism between the two benches, and independent actuating mechanism for each of the upper frames and separably connected to the main driving mechanism for causing said frames to operate either simultaneously or individually and also for permitting the upper frames to be manually raised.

In testimony whereof I have hereunto set my hand in presence of two subscribing witnesses.

ROGER EADES.
